SPECTACLE CASE

Arthur J. Pratt, Belmont, Mass., assignor to
American Optical Company, Southbridge,
Mass., a voluntary association of Massachu-
sets

Application January 4, 1943, Serial No. 471,241

4 Claims. (Cl. 206—5)

This invention relates to receptacles and has particular reference to a novel case for spectacles.

One of the principal objects of the invention is to provide a simple, practical and inexpensive case for sunglasses or other spectacles and more particularly simple and efficient closure means.

Another object of the invention is to provide a novel spacer member between the walls of a spectacle case which will also serve as a guide for the closure means.

Other objects and advantages of the invention will become apparent from the following description taken in connection with the accompanying drawing, and it will be apparent that many changes may be made in the details of construction, and arrangement of parts shown and described, without departing from the spirit of the invention as expressed in the accompanying claims.

I, therefore, do not wish to be limited to the exact details shown and described as the preferred form only has been given by way of illustration.

Referring to the drawing:

Fig. 1 is a front elevation of the spectacle case showing a pair of spectacles therein.

Fig. 2 is a side elevation of the spectacle case shown in Fig. 1 without the spectacles.

Fig. 3 is a sectional view taken on line 3—3 of Fig. 1 and looking in the direction indicated by the arrows, without showing the spectacles.

In the past with spectacle cases of this nature, the closure means used were of the snap fastener type which comprised two members, one attached to the flap and one attached to the front wall thereof. This meant that besides the additional parts used in the case, extra labor costs were added for assembling the different parts, thus tending to make the case more expensive.

Another difficulty encountered with this type of closure means was that one part of the snap fastener was attached to the front wall of a case and was adapted to bear against the spacer block between the two walls of the case or attached to the spacer block and the front wall. With this type of construction, pressure was needed to connect the two snap fastener members and this sometimes was enough to break the spacer block, with the result that the spectacle frame would be bent and the lenses might possibly be broken. Different means of reinforcements have been used to support the spacer block but that also added to the cost of the case.

Tongue and slot means, as shown in the pres-

ent invention, for means of closure have previously been used on different articles but in most instances, difficulty was encountered in threading the tongue through the slots.

In the present invention, it is believed that new and novel means have been found to overcome all of the above difficulties, as will become apparent from the following description.

Referring more particularly to the drawing wherein like characters of reference designate like parts throughout the several views, the receptacle embodying the invention, as shown in Figs. 1, 2, and 3, comprises broadly a spectacle case 5, preferably constructed of a flexible material such as leather, cloth or the like. This case comprises a rear wall 6 and a front wall 7 which are united throughout their lower edge and side portions by means of stitching or other suitable means, to provide a pocket for receiving a spectacle. The rear wall 6 is provided with a central extension 8 which is adapted to be folded over the open top of the case and is provided with a further extension located centrally thereof to form a tongue or tab 9.

The front wall 7 of the case is provided with two spaced longitudinal slits 10 and 11 whereby the portion between the slits may be raised to provide loop means 21 for receiving the tongue 9 to provide closure means for the case.

A wedge-shaped spacer member 12 of wood or other suitable material is interposed between the front and rear walls 6 and 7 centrally thereof with the thickest end up, and is adapted to be attached to the rear wall 6 by adhesive or other suitable means. This is for the purpose of spacing the upper walls from each other to permit a spectacle to be placed within the case.

The spacing member 12 is provided with a recess in its lower front surface having a groove 13 therein. The recessed portion of the spacing member 12 is adapted to receive the portion 14 of the front wall 7 adjacent the slit 10, with the upper edge of the portion 14 lying within the groove 13. This causes the adjacent edge surfaces formed by the slit 10 to be spaced from each other in a horizontal direction.

The adjacent edge surfaces are held in this relation by means of the front surface 20 of the spacer block and through the anchoring function of the groove 13 in which the upper edge of the portion 14 is fitted.

If desired the groove 13 may be omitted in which instance the upper portion 14 may be secured to the underlying part of the spacer block

or in a surface of the recess by suitable cement, adhesive or other means.

It is also apparent that instead of forming a recess in the lower portion of the block only a groove simulating the groove 13 may be formed in the lower surface of the block in which the portion 14 may be fitted and held in spaced relation with the loop portion 21.

A portion of the front wall 7 will lie against the front surface of the spacer member 12 in spaced relation with the rear wall 6, thus providing a pocket in which a sunglass or spectacle may be placed. It will be noted that the bridge 16 of a spectacle when placed in the case will be positioned about the spacer block 12.

The upper portions 17 of the front wall 7 are cut away at the ends of the case to provide spaces 18 between the edges of the back wall 6 and the edges of the front wall 7. This is to permit the temples 19 of a pair of spectacles to be folded over the front wall 7 when said spectacles are placed in the case.

When a sunglass or spectacle is placed in the case and the temples 19 are in folded position against the outer surface of the front wall 7, the central extension 8 of the rear wall 6 is folded over the frame and temples and the tongue or tab 9 is threaded through the loop formed by the slits 10 and 11 to hold the spectacle securely therein.

It is to be noted that when the tongue or tab 9 is threaded into the slit 11 it will engage the side surface 20 of the spacer member 12 and further pressure downward will cause the tab to slide downwardly along the side surface 20 of the spacer member 12 and out of the slit 10, without contacting the lower edge portion 14 formed by the slit 10. This does away with the difficulty usually encountered with closure means of this nature, as the spacer member 12 acts as a guide for the tongue or tab 9 when said tongue is being inserted through the loop 21 formed by the slits 10 and 11. The spacer member 12 also holds one edge portion 14 which is formed by the slit 10 in horizontal spaced relation with the other edge portion 24 formed by the slit 10 to allow the tongue or tab 9 to be quickly and easily threaded through the loop 21 which is formed in the front wall 7 by the slits 10 and 11.

The spacer member 12 as shown in Fig. 3 is provided with tapered side walls 20 and 22 with the thickest portion at the top, this is for the purpose of holding the walls 6 and 7 in spaced relation with each other at their upper sides so that a spectacle may be quickly and easily placed within the case.

Another advantage derived from having a spacer member of this shape is that the wider upper portion of the block will tend to cause the opposed edges 23 and 25 of the slit 11 to pinch or squeeze the tongue or tab 9 therebetween when the case is closed. This will tend to hold the tab 9 from working out of the loop 21. The lower front edge of the block 12 adjacent the recess for the portion 14 will also function cooperatively with the lower edge 24 to hold the tab 9 from working out of the loop 21 during the use of the case.

Although the rear wall 6 has been described as the only wall which is secured to the spacer block 12, the portion of the front wall 7 lying above the loop 21 and which overlies the front surface of the block 12 and the portion 14 which lies within the lower recess may also be secured to said block 12 as by adhesive or other suitable

means. This, therefore, would leave only the loop portion 21 unsecured in the vicinity of the spacer block 12.

Although the spacer block 12 has been described as being tapered, it is to be understood that any suitable shape of block may be used depending upon the requirements of the receptacle.

From the foregoing description it will be seen that simple, efficient and economical means have been provided for accomplishing all the objects and advantages of the invention.

Having described my invention, I claim:

1. A spectacle case composed of rear and front walls connected together along their bottom edges and part of their end portions to provide a pocket for a pair of spectacles, said rear wall having at its top an elongated portion centrally disposed thereof to form a closure flap, an outwardly extending loop formed centrally on the front wall of the case to be used in conjunction with the said flap for providing closure means, said loop being formed by vertically spaced slits in said front wall, a spacer member located between the said rear and front walls adjacent said loop and attached to the rear wall to space the said walls from each other and a recess in the bottom of said member and spaced rearwardly of the front surface of said spacer member receiving that edge portion of the front wall which lies immediately below the lower of said spaced slits.

2. A flexible spectacle case comprising rear and front walls connected together at their bottom and edge edges to provide a pocket for a pair of spectacles, said rear wall having at its top an elongated portion centrally disposed thereof to form a closure tab, a loop formed centrally of the front wall of the case to be used in conjunction with said tab for providing closure means for the case, said loop being formed by vertically spaced slits in said front wall, said front wall having cut out portions at its opposed ends to allow the temples of a spectacle to be folded externally thereof, a wedge-shaped spacer member located between the said rear and front walls adjacent the loop member so as to taper in a downward direction and having one of its tapered surfaces attached to the rear wall to space the said walls from each other, said spacer member having a recess therein adjacent the lower edge of the front tapered surface of said spacer member and disposed in the rear of the plane of said front surface and said front wall, below the lower of said spaced slits, having a portion thereof positioned within the recess.

3. A spectacle case comprising rear and front walls connected together at their bottom and side edges to provide a pocket for receiving a pair of spectacles, one of said walls having spaced slits therein and the other having at its top an elongated portion terminating in a reduced tongue-like member adapted to be extended through the spaced slits, a wedge-shaped spacer member located between said front and rear walls with the taper disposed in a downward direction and having a recessed portion located adjacent the lower of said spaced slits and having a portion of the wall below said lower slit positioned therein whereby the portion of the wall lying within said recessed portion will be positioned rearwardly of the plane of the adjacent tapered surface of the spacer member.

4. A receptacle comprising front and rear wall portions secured adjacent their bottom and part of their side edges to provide a pocket, one of

said wall portions having spaced slits therein forming a loop and the other of said wall portions, on the side thereof opposite the pocket having a portion with a reduced tongue adapted to be extended through said loop and a spacer member between said wall portions having front and rear surfaces tapering downwardly towards each other with the lower portion of said spacer mem-

ber having a transversely extending recessed portion in which the portion of the wall below the lower of said slits is positioned and retained with the plane of its outer surface disposed rearwardly of the plane of the adjacent tapered side surface of said spacer member.

ARTHUR J. PRATT.
